UNITED STATES PATENT OFFICE.

AUGUST FINNILA, OF LOS ANGELES, CALIFORNIA.

BAKE-OVEN.

1,152,803.

Specification of Letters Patent.

Patented Sept. 7, 1915.

Application filed June 8, 1914. Serial No. 843,883.

To all whom it may concern:

Be it known that I, AUGUST FINNILA, a citizen of the United States, residing at Los Angeles, in the county of Los Angeles and State of California, have invented a new and useful Bake-Oven, of which the following is a specification.

An object of this invention is to provide for baking articles more uniformly and with less liability of under and over baking them than with ovens heretofore in use.

Another object is to effect even heating of the baking chamber and especially to avoid over heating the front corners of the floor of said chamber.

Another object is to utilize the heating medium to the best advantage for the sake of economy and uniform heating.

Another object is the production of an oven which will have maximum resistance against disintegrating effect of the usual baking temperatures.

To contribute toward the foregoing objects the top and bottom of the baking chamber are formed of separate flues or tubes and the baking floor itself is thicker at some portions than at others so that the hotter gases of combustion will produce substantially the same temperature at those portions of the floor under which the gases enter as the cooler gases will produce for other portions of the floor and the top tubes are so constructed as to more freely admit the gases to the tubes nearer the sides than to the tubes nearer the center.

Further objects and advantages may appear as the invention is unfolded in detail in the subjoined description and as shown in the drawings filed herewith.

The accompanying drawings illustrate the invention.

Figure 1 is a front elevation of a baking oven built in accordance with this invention looking at the left end of Figs. 3 to 6, both doors of the fire box being open and the chimney being partly broken away to contract the view. Fig. 2 is a sectional elevation on irregular line indicated by x^2-x^2 , Fig. 4. Fig. 3 is a longitudinal sectional elevation on irregular line indicated by x^3-x^3 , Figs. 2, 4 and 6. Fig. 4 is a plan section partly on irregular line indicated by x^4-x^4 , Figs. 2 and 3 and partly on line indicated by x^{4a} , Fig. 3. Fig. 5 is a longitudinal sectional elevation on irregular line indicated by x^5-x^5 , Fig. 6. Fig. 6 is a plan

section on irregular line indicated by x^6-x^6 , Figs. 2 and 3, the doors of the fire box being closed.

Arrows on the section lines in the various views indicate the direction of sight.

The oven is provided with front, rear and side walls 1, 2, 3, top 4 and bottom 5, all constructed of brick or the like. Midway between the side walls 3 there is provided a longitudinally extending rectangular fire box 6 communicating at its front end through a grating 7 with a pit 8 which is below the level of the fire box and which extends beneath the front wall 1 and which is provided at its front end with a grill 9 whereby air is admitted to the fire box. The fire box 6 opens at its front end through the front wall 1 and it is especially noted that the fire box is provided with two spaced apart doors, an inner door 10 and an outer door 11 and that a burner 12 is accommodated in the space 13 between said doors when the burner is not in use, and said burner is swiveled at 14 so that it may be swung rearward and project into the fire box when the inner door 10 is opened for that purpose.

By the foregoing construction the fire box may be quickly heated by putting the burner 12 in commission and closing the outer door 11 and the heat may be effectively retained by closing the two doors 10, 11.

Above the plane of the fire box 6 are arranged longitudinally extending parallel open ended flues or tubes 15 constructed of fire brick or the like and forming the bottom or floor of a rearwardly reduced baking chamber 16 of greater width than the fire box, said floor being aslant upward from front to rear so that the space between the baking chamber and fire box is greater at the rear than at the front, said space being all suitably built up solid with brick or the like with the exception of the space occupied by the tubes 15, and the bores of said tubes are substantially horizontal so that the floor space between the tubes and the baking chamber is greater at the rear ends of the tubes than at the front ends of said tubes. This thickening of the baking chamber floor rearwardly is of advantage to insure even heating of the floor slabs 17 from front to rear of the baking chamber, for the gases from the fire box 6 pass through lower transversely extending rear flues 18 into the

rear ends of said tubes, in consequence of which, the temperature of said gases is higher at said rear ends than it is at the front ends where the gases pass from said tubes after having parted with some of their heat. It is noted that the tubes 15 are arranged in two separate banks or series, a right series and a left series, each series being independent of the other by reason of a partition 19 that may be an arch forming the roof of the fire box 6. The floor of the baking chamber 16 not only thickens rearwardly as clearly shown in Figs. 3 and 5 but also thickens at the front from the center toward the sides as clearly shown in Fig. 2 and for this purpose the front ends of the tubes 15 are deflected downward increasingly from the center toward the sides, the floor slabs 17 being horizontal from the center to the sides, so that there will be no tendency to over heating of the floor slabs at the front corners. The baking chamber 16 opens at its front end through the front wall 1 and is there provided with a counterbalanced door 20. Provision is made for supplying steam to the baking chamber 16 and for this purpose a steam pipe 21 led from a suitable source of supply, not shown, passes through the front wall 1 into the front end of the baking chamber 16 and said pipe is provided with a suitable valve 22. By this construction the air in the baking chamber 16 may be moistened to produce any desired percentage of humidity for producing superior baked foods.

The top of the baking chamber 16 is constructed of longitudinally arranged parallel open ended flues or tubes 23, preferably arranged from side to side in the form of an arch and said tubes may be formed of fire tile or the like placed end to end. The tubes 23 are not all of the same length but increase in length from the sides toward the center and the rear ends of said tubes are flush with one another so that the front ends of the more central tubes are stepped forward beyond the front ends of the tubes nearer the sides. The forward ends of the tubes 23 are spaced apart from the front wall 1 to form upper transversely extending front flues 24 which are separated one from the other by a partition 25 that extends from the front wall 1 to the rear wall 2 and that thus separates said tubes into two banks or series, a left series and a right series.

The front walls of the upper front flues 24 are aslant forwardly from the sides toward the center to accommodate the forward stepping of the flues 23 but the slant of said walls is not as great as the slant represented by the stepping of the tubes 23 so that the front ends of those of the tubes that are nearer the sides are spaced farther away from said front walls than the front ends

of the more central tubes, thus diminishing the inlets into said tubes from the sides toward the center so that the tubes nearer the sides will receive more heat than the tubes nearer the center, thus tending, as I have discovered, to equal heating of the baking chamber. The upper front flues 24 open into vertical flues 26, one in each front corner, said flues extending downward in front of the forward ends of those bottom tubes 15 that are nearer the sides, and all of said bottom tubes being spaced apart from the front wall 1 sufficiently to form lower transversely extending front flues 27. The rear ends of the top flues 23 are spaced apart from the rear wall 2 to form upper transversely extending rear flues 28 which open into a chimney 29. The top tubes 23 are spaced apart from the top 4 of the oven, the space being formed into a double bank of heat-insulating dead air chambers in the form of upper cells 30 and lower cells 31 and, as shown in the drawings, the top tubes 23 and cells 30, 31 may all be formed by fire tile provided with three separate passages placed end to end.

Where it is preferable to use fire brick and fire tile, the same have been indicated in the drawings by closer section lining than the other parts.

As the floor of the baking chamber 16 at the front corners is thickened from the center toward the sides so also is the front wall 1 adjacent the baking chamber thickened considerably from the center toward the sides, as clearly shown by dotted construction lines 32 in Fig. 4, for the purpose of obtaining even conduction of heat by said partition from the hot gases in the flues 26. Along both sides of the fire box 6 beneath the bottom flues 15 are provided heat-insulations in the form of sand-beds 33. The chimney 29 is provided with a damper 34 operated from the front by a damper rod 35.

Provision is made for rapidly lowering the temperature of the baking chamber 16 and for this purpose the baking chamber is provided with air vents 36 opening at their forward ends at both sides near the front end of said chamber, and extending upward at the sides of the chimney 29 to the top thereof so as to provide a strong draft tending to draw hot air out of the baking chamber. The vents 36 are provided with dampers 37 which are operated from the front by damper rods 38.

The fire box 6 is provided at its rear end with a vertically extending V-shaped deflector 39 projecting from the rear wall 2 in the median line of said fire box so as to divide the gases of combustion and cause them to flow in equal quantities to the right and left into the lower rear flues 18. When it is desired to use the bake oven, the doors 10, 11 will be opened and the burner 12

will be swung into the position shown in Fig. 1, and the fuel supplied by said burner will be lighted and the outer door 11 will then be closed. Then when the oven has 5 reached the desired baking temperature which may be indicated by the thermometer 40, the articles to be baked will be placed in the baking chamber 16.

The air passing into the fire box 6 through 10 the grill 9 will be heated by the burning gases and together with the gases of combustion will flow toward the rear, heating the top 19 and also partly heating by conduction through the sides of the fire box the 15 bottom tubes 15; thence to the right and left through flues 18 into the rear ends of the bottom tubes 15; thence forward in said tubes further heating the floor slabs 17; thence to the left and right in the flues 27; 20 thence upward through the flues 26 into the front ends of the top tubes 23, thence rearward through said top tubes to heat the top of the baking chamber; thence into the flues 28 and thence through said flues 28 toward 25 the center and by way of the chimney to the atmosphere.

When the oven is sufficiently hot within the judgment and experience of the baker, the fuel may be cut off from the burner 12 30 and said burner may be swung into the position shown in solid lines, Figs. 5 and 6 and the inner door 10 will then be closed and the baking process will continue until the articles have been baked, whereupon said 35 articles may be removed and other articles placed in the baking chamber for baking, and from time to time the burner may be put into commission to maintain the oven at a desired baking temperature or to increase 40 the temperature. If the oven is too hot and bakes too quickly, the temperature of the baking chamber 16 will be readily lowered by opening the door 20 and operating the dampers 37 to open the vents 36 so that the 45 hot air will be drawn out of said chamber. As the baking process proceeds the valve 22 may be opened from time to time as desired to supply moisture to the baking chamber so as to prevent burning of the articles being 50 baked.

I claim:—

1. A bake oven comprising a fire box, a baking chamber of greater width than the fire box, the top and bottom of said chamber each being formed of a series of separate tubes, the top and bottom tubes being in communication with one another at their front ends, a dead air cell along the upper side of each of the top tubes the bottom 55 tubes at their rear ends communicating with the fire box, and a chimney in communication with the rear ends of the top tubes.

2. A bake oven comprising a fire box, a baking chamber above the fire box, the top 60 of said fire box forming a portion of the

bottom of the baking chamber, the top and another portion of the bottom of said chamber each being formed of right and left separate series of longitudinal tubes, a right vertical flue and a left vertical flue connecting the front ends of the right top and bottom and the left top and bottom series respectively of the longitudinal tubes, the rear ends of the bottom tubes being in communication with the fire box, and a chimney 75 communicating with the rear ends of the top tubes.

3. A bake oven provided with a baking chamber having its floor partially formed of longitudinally arranged tubes, and a fire 80 box connected to said tubes, the top of said fire box partially forming the floor of the baking chamber.

4. A bake oven provided with a baking chamber having its top formed of tubes, a 85 dead air cell along the upper side of each of said tubes and a fire box connected to said tubes.

5. A bake oven provided with a baking chamber having its floor and top formed of 90 tubes placed side by side, said tubes communicating with one another at their front ends, an upper and a lower dead air cell along the upper side of each of the top tubes and a fire box connected to the rear ends of 95 the floor tubes.

6. A bake oven, comprising a baking chamber having its floor formed of tubes, said floor increasing in thickness at the front end from the center toward the sides, 100 and a fire box connected to the rear ends of said tubes.

7. A bake oven, comprising a baking chamber having its floor formed of tubes, said floor increasing in thickness from front 105 to rear and also increasing in thickness at the front from the center toward the sides, and a fire box connected to the rear ends of said tubes.

8. A bake oven comprising a fire box, a 110 baking chamber having its top formed of longitudinally arranged tubes and communicating with the fire box through inlets diminishing from the sides toward the center so that the tubes nearer the sides will receive more heat than the tubes nearer the center, and a chimney connected with the rear ends of said tubes.

9. A bake oven comprising a baking chamber having its top formed of longitudinally arranged tubes, the forward ends of the tubes being spaced apart from the front wall to form transversely extending flues and the front ends of the more central tubes being stepped forward beyond the forward 120 ends of the tubes nearer the sides, a fire box connected with the forward ends of the tubes, and a chimney connected with the rear ends of said tubes.

10. A bake oven comprising a fire box, a 130

- baking chamber above the level of said fire box and having its top and the side portions of its bottom formed of tubes, the top of the fire box forming the median portion of said bottom, partitions separating said tubes into right and left series for both top and bottom, the ends of the top tubes being spaced apart from the front and rear walls to form upper front flues and upper rear flues respectively and the ends of the bottom tubes being spaced apart from the front and rear walls to form lower front flues and lower rear flues respectively, said lower rear flues opening into the fire box, a vertical flue at each front corner opening into the upper and lower front flues, and a chimney connected with the upper rear flues.
11. A bake oven comprising a fire box, a baking chamber above the level of said fire box and having its top and bottom formed of tubes, partitions separating said tubes into right and left series for both top and bottom, the ends of the top tubes being spaced apart from the front and rear walls to form upper front flues and upper rear flues respectively and the ends of the bottom tubes being spaced apart from the front and rear walls to form lower front flues and lower rear flues respectively, said lower rear flues opening into the fire box, a vertical flue at each front corner opening into the upper and lower front flues, the floor of the baking chamber being thickened from front to rear and said floor also increasing in thickness at the front end from the center toward the sides and the front wall adjacent the baking chamber being thickened from the center toward the sides, and a chimney connected with the upper rear flue.
12. A bake oven comprising a longitudinally extending fire box, a baking chamber of greater width than and above the level of the fire box and having its top and floor formed of open ended tubes, said top tubes being spaced apart from the top of the oven

by dead air cells and said floor being astant upward from front to rear and thicker at the rear end between the bores of the floor tubes and the baking chamber than at the front end, flues connecting the front ends of the top tubes to the front ends of the floor tubes, and a chimney connected to the rear ends of the top tubes, the rear ends of the floor tubes communicating with the fire box.

13. A bake oven comprising a baking chamber, flues above and below the baking chamber connected with one another, a fire box connected with said flues and opening through the front wall of the oven, an inner and an outer door spaced apart from one another at the open end of the fire box, and a burner mounted in the space between the inner and outer doors.

14. A bake oven comprising a fire box, a baking chamber above the fire box and separated therefrom by a partition forming a portion of the floor of the baking chamber, tubes on both sides of the partition forming other portions of the floor of the baking chamber and separated thereby into right and left series, separate flues connecting the fire box to the right and left series respectively, a chimney, and other separate flues connecting the chimney to the right and left series respectively.

15. A bake oven comprising a baking chamber having its top constructed of hollow tiles end to end to form an arch, each having separated bores and the lower bores forming flues and the upper bores forming dead air cells, a fire box connected to the front ends of said flues, and a chimney connected to the rear ends of said flues.

In testimony whereof, I have hereunto set my hand at Los Angeles, California this 1st day of June 1914.

AUGUST FINNILA.
